UNITED STATES PATENT OFFICE.

SYLVANUS STEVENS, OF GRAYLING, MICHIGAN.

SALT-CELLAR.

SPECIFICATION forming part of Letters Patent No. 735,169, dated August 4, 1903.

Application filed March 31, 1903. Serial No. 150,351. (No model.)

To all whom it may concern:

Be it known that I, SYLVANUS STEVENS, a citizen of the United States, residing at Grayling, in the county of Crawford and State of Michigan, have invented certain new and useful Improvements in Salt-Cellars, of which the following is a specification, such as will enable those skilled in the art to which it appertains to make and use the same.

10 The object of this invention is to provide a salt-cellar with an improved attachment whereby the salt when it becomes hard may be broken up or pulverized and shaken through a perforated top; and with this and 15 other objects in view the invention consists in a device of the class specified constructed as hereinafter described and claimed.

The invention is fully disclosed in the following specification, of which the accompanying drawings form a part, in which the separate parts of my improvement are designated by suitable reference characters in each of the views, and in which—

Figure 1 is a central vertical section of a salt-cellar provided with my improvement; Fig. 2, a perspective view of a modified form of the attachment; Fig. 3, a similar view of the attachment as shown in Fig. 1, but removed from the salt-cellar; and Fig. 4, a plan 30 view of the cap of the salt-cellar.

In the drawings forming part of this specification I have shown at *a* an ordinary salt-cellar provided with a perforated cap *b*, which is adapted to be connected therewith by means 35 of a screw-thread or in the usual manner, as shown at *c*.

The cap *b* of the salt-cellar is provided with a circular opening *d*, and in the practice of my invention I provide an attachment *e*, comprising a shank portion *e²*, having spring handles or arms *e³* at its upper end, and a stirrer, breaker, or agitator *e⁴*. The part *e⁴*, as shown in Figs. 1 and 3, consists simply of a plate secured to the lower end of the shank *e²* in any 45 desired manner; but in the form of construction shown in Fig. 2 this part consists of a rectangular frame. The shank *e²* in the form of construction shown is composed of twisted wire, and the separate strands of wire are 50 separated at the upper end to form handles

or arms *e³* and at the lower end to form the member *e⁴*.

The handles or arms *e³* are provided on their outer sides each with a notch or recess *e⁵*, and the edge walls of the opening *d* in the cap *b* fit in these notches or recesses. In order to break up solidified salt, the attachment may be used as a plunger, and in this operation the spring handles or arms *e³* are pressed together and the device is moved up and down, 60 as will be readily understood. The device may also be used for the purpose of breaking up or pulverizing the salt by simply rotating it within the salt-cellar, and this is done by means of the handles or arms *e³*, as will be 65 readily understood.

The attachment is not removable from the cap *b*; but said cap may be removed whenever desired in the usual manner.

The attachment may be rotated as herein-before described and for the purpose specified without having the cap portion *b* fitting in the notches or recesses *e⁵*; but these notches or recesses prevent the attachment from being moved longitudinally through the cap *b* 75 when said cap fits therein; but the attachment may be used either as a plunger or as a rotatable device in any position in which it is desired to hold it.

This device is simple in construction and 80 operation and comparatively inexpensive and is well adapted to accomplish the result for which it is intended.

Having fully described my invention, what I claim as new, and desire to secure by Letters 85 Patent, is—

1. A salt-cellar provided with a removable perforated cap having a central opening, and an attachment which is adapted to be inserted into the salt-cellar and which comprises a shank having upwardly-directed spring-arms which pass through the opening in the cap and which engage said cap, said shank being provided at its lower end with a breaker or stirrer, substantially as shown and described. 95

2. A salt-cellar provided with a removable perforated cap having a central circular opening, and an attachment which is adapted to be inserted into the salt-cellar and which comprises a shank having upwardly-directed 100

spring-arms which pass through the opening in the cap, said shank being provided at its lower end with a breaker or stirrer, and said spring-arms being provided in their outer sides with notches or recesses, substantially as shown and described.

5 In testimony that I claim the foregoing as

my invention I have signed my name, in presence of the subscribing witnesses, this 26th day of March, 1903.

SYLVANUS STEVENS.
